UNITED STATES PATENT OFFICE.

LEO IGNATIOUS BRADDOCK, OF NEW SYMRNA, FLORIDA.

CAPPING FOR STUCCO WALLS.

Application filed May 18, 1925. Serial No. 31,101.

To all whom it may concern:

Be it known that I, LEO IGNATIOUS BRADDOCK, a citizen of the United States, residing at New Smyrna, in the county of Volusia and State of Florida, have invented certain new and useful Improvements in a Capping for Stucco Walls, of which the following is a specification.

There is a well known type of house which 10 is popular in certain portions of this country and is commonly known as the Spanish type. It has always been a problem to the builder and architect in carrying out the Spanish design, at the top of the parapet 15 wall, in that there has never been any efficient means designed whereby the builder could carry the plaster or stucco to the top of the wall without the showing of metal or wood.

20 The principal object of the present invention is to provide means whereby it is possible to carry the plaster or stucco to the very top of the parapet wall without showing any metal, wood, or other anchoring 25 means.

Another important object of the invention 30 is to provide a means of this nature which is simple in its construction, thoroughly reliable and efficient, strong, durable, easy to incorporate in the wall structure, and otherwise well adapted to the purpose 35 for which it is designed.

With the above and numerous other objects in view as will appear as the description 35 proceeds, the invention resides in certain details of construction as will be hereinafter more fully described and claimed.

In the drawing:—

Figure 1 is a sectional view through the 40 upper portion of a parapet wall with my improved anchor and cap attachment associated therewith, and

Figure 2 is a fragmentary detail enlarged 45 perspective view of a portion of the anchor and cap.

Referring to the drawing in detail, it will be seen that the parapet wall shown in Figure 1 comprises the wooden lath portion 1, the rear portion 2, and the top 3, which are 50 all of conventional construction. The roof is indicated at 4 and extends rearwardly from the rear portion 2 in the usual manner. The plaster or stucco is indicated at 5 and engages the lath structure 1 by the 55 dove tail tongue and groove connection 6 as is usual.

My improvement consists of a tapping plate 7 which has one or both ends provided with an inverted U-shaped extension indicated at 8 and formed integral with the 60 depending flange 9. One side of the extension 8 lies along the inner side of the flange 9, the intermediate portion of the extension 8 lies under the plate 7, and the other side of this extension is perpendicularly disposed 65 into the plate 7. The flange 9, and the adjacent side of the extension 8 may be provided with registering apertures 10. The plate 3 is placed on the top 7 so that the extension 8 depends along the front surface 70 of the lath structure 1. If a similar extension 8 is provided on the other end of the plate, this will overhang a lath structure also. As shown in Figure 1, however, the rear portion 2 is of that nature which would 75 not be seen, and therefore a flange 11 is merely provided for engaging the rear 2. The plaster and stucco is applied in the usual manner so as to extend into the channel of the extension 8, and about the flange 80 9, and over the top of the adjacent portion of the plate 7, as is clearly shown in Figure 1. If desired, fastening element such as spikes 11 may be driven through the stucco, through the openings 10, and so as to pierce 85 the other side or inner side of the extension 8, and the lath structure 1.

With this improved cap and anchoring device it is possible to carry the stucco above 90 the top 3 without the necessity of showing any wood or metal as is now the common custom.

It is thought that the advantages, construction, and utility of my invention will 95 now be clearly understood by those familiar with the Spanish type of houses having the parapet walls without a more detailed description. It is apparent, however, that changes in the details of construction may be resorted to without departing from the 100 spirit or scope of the invention as herein-after claimed or sacrificing any of its advantages.

Having thus described the invention, what I claim as new and desire to secure by Letters Patent is:—

1. In combination, a parapet wall including a lath structure and a top, a plate disposed over the top and having an inverted U-shaped extension on its end depending in 110 front of the lath structure, and stucco applied to the lath structure to extend in and

about the extension and over the adjacent portion of the plate.

2. A device of the class described including a plate body, a flange depending from one edge of the plate body and merging into an inverted U-shaped extension having one wall lying alongside the flange.

3. A device of the class described including a plate body, a flange depending from one edge of the plate body and merging into an inverted U-shaped extension having one wall lying alongside the flange, said flange and the side of the extension adjacent thereto being provided with registering openings.

4. In a parapet wall structure wherein a stucco is applied to the lath structure, a cap and anchoring device comprising a plate for resting on top of the parapet wall structure and extending beyond the lath structure, a flange depending from the edge of

the plate beyond the lath structure and merging into an inverted U-shaped extension having the adjacent side disposed against the flange.

5. In a parapet wall structure wherein a stucco is applied to the lath structure, a cap and anchoring device comprising a plate for resting on top of the parapet wall structure and extending beyond the lath structure, a flange depending from the edge of the plate beyond the lath structure and merging into an inverted U-shaped extension having the adjacent side disposed against the flange, said flange and the adjacent side of the extension provided with registering openings, and fastening elements adapted to pierce the stucco, the openings, and the laths structure.

In testimony whereof I affix my signature.

LEO IGNATIOUS BRADDOCK.
